TO MAGIC DEVICE CORPORATION, OF HOBOKEN, NEW JERSEY, A CORPORATION OF
NEW JERSEY.

VENDING MACHINE.

Application filed March 24, 1925. Serial No. 17,868.

The invention relates to vending machines, and more particularly to an electrically actuated vending machine wherein the closing of an electric circuit will establish conditions in the machine which will permit a purchaser to select and cause the delivery of one of a number of different articles stored in the machine.

A vending machine embodying the invention is so constructed as to permit the storage of a number of articles to be sold, each article being in a separate compartment from which it may be withdrawn and delivered to the purchaser, by a slide which may be operated by an electro-magnetic plunger, the circuit to which is closed as a result of the deposit of a coin or check in the machine, and opened by the article being delivered, thus preventing the actuation of any slide except upon the deposit of a coin or check in the machine, and limiting the potential actuation of the machine to the delivery of a single article.

In a machine embodying the invention, it is possible to vend a considerable variety of articles of different sizes and shapes, since the delivery mechanism is operative only as to a single article at a time, and the delivery of this article does not in any way disturb the articles in any other compartment than that in which the delivery slide is actuated by the magnetic actuating member.

In the event that an article is not delivered with the actuation of one of the slides, the construction is such that the circuit which energizes the magnetic plunger remains closed, thus permitting the purchaser to operate the machine a second time, or repeatedly until an article is actually delivered, the circuit to the magnetic plunger being opened only upon the delivery of an article, and not through the automatic action of the mechanism by which the circuit to the plunger is closed, or any mechanism having a time interval within which the delivery of the article must be effected.

Each slide is so positioned with relation to openings in the front of the casing as to permit a magnetic plunger, when passed through an opening, to be brought into the operative relation to the slide. To prevent the unauthorized operation of the machine arising from this condition, each slide is so constructed that its actuation in any manner

except by the use of the electro-magnetic plunger is impossible, thus preventing the defrauding of the machine by the use of wires, sticks, or other devices which may be engaged with the slide or caused to adhere thereto.

To facilitate the recharging of the device, the various compartments and slides are made in a unitary structure in the form of a magazine, the various compartments of which may be readily filled in a storeroom, so that a magazine in which the merchandise is partially or wholly exhausted, may be quickly removed from the machine and replaced by a completely charged magazine.

It will readily be understood that the mechanisms of the machine should be completely inclosed, excepting the delivery shelf and the openings by which the electro-magnetic plunger may be brought into the operative relation to the various delivery slides.

In order to prevent tampering with the machine, unless a coin or check has been properly inserted in the slot, we preferably so form the electro-magnetic plunger that it cannot be brought into operative relation to any slide until its magnet has been energized as a result of the actuation of the circuit closing mechanism provided for the purpose of making the machine operative.

In the machine of the invention, the mechanisms employed are so simple as not to be subject to disarrangement from any cause whatsoever excepting the exhaustion of the battery or other source of electrical supply. The mechanism may be, and preferably is, so constructed as to contain all of the elements necessary to its operation, thus permitting its use upon counters or in other positions where electrical outlets from a lighting circuit are not available.

In addition to the possibility of offering for sale a variety of articles of merchandise, the mode of operation of the machine is such as to arouse keen interest in a prospective purchaser, not only because a selection of dissimilar objects is permitted, but because of the unusual, though slight, effort required on the part of the purchaser in operating the machine to cause the desired article to be delivered.

It will be noted that irrespective of the position of the article to be delivered, one and the same mechanism is used throughout

the machine, although if desired different units containing merchandise having different values may be associated in the same casing but in different magazines, in which case, however, each unit will have its own independent actuating mechanism, the setting of which, however, will vary according to the size of the coin or check required to represent the value or price of the article to be delivered.

The invention consists primarily in a vending machine embodying therein a casing, a plurality of merchandise receiving compartments, a slide containing electro-magnetic material in each compartment and engaging the merchandise therein, whereby movement of said slide outwardly of the compartment will eject the merchandise from the compartment, said casing having openings therethrough, an electro-magnetic plunger adapted to be passed through any of said openings into operative relation to a slide, a source of electrical supply, means arranged in circuit with said plunger and said source of supply whereby said plunger may be energized upon the insertion of a check, a delivery shelf adapted to receive articles, and means operable as a result of the delivery of an article by the machine for making said last named means inoperative; and in such other novel features of construction and combination of parts as are hereinafter set forth and described, and more particularly pointed out in the claims hereto appended.

Referring to the drawings,

Fig. 1 is a front view of a vending machine embodying our invention, partly broken away;

Fig. 2 is a section on the line 2—2 of Fig. 1;

Fig. 3 is a perspective view showing in detail the construction of the several slides of a magazine; and

Fig. 4 is a diagrammatic showing of the electrical conditions in the machine.

Like numerals refer to like parts throughout the several views.

In the embodiment of the invention shown in the drawings, the outer casing of the machine is indicated at 10, the back of this casing being closed by a removable back plate

11, permitting access to the machine for the purpose of removing therefrom, or placing

therein, a magazine, removing the coins or checks, and renewing the primary or secondary battery, which may, and preferably does, constitute the source of electrical supply for the operation of the machine.

The front of the casing is formed of a sequence of vertically extending strips 12 each having a plurality of openings 13 therethrough, the space between these strips being closed by lights of glass 14. Rearwardly of the casing is a

partition 15 supporting the magazine in

which the merchandise to be sold is stored. This magazine is spaced from the front of the machine as shown more particularly in Fig. 2 and the sides and top portion of the casing corresponding with the space between the magazine and the front of the machine, are closed by means of lights of glass 16 to secure a better illumination of the magazine structure.

The magazine consists of a plurality of compartments 17 formed by horizontal partitions 18 and vertical partitions 19, these compartments being arranged in vertical tiers, one tier being positioned rearwardly of each strip 12 and each compartment being substantially centered in relation to an opening 13 in said strip. Any desired number of tiers of these compartments may be used in a machine, or in each unit of a machine, the delivery of the merchandise contained in each compartment being effected by one and the same mechanism controlled from a single source such as the coin or check slot 20. The partitions 18 and 19 are preferably made of non-magnetic material so as not to interfere with the free movement of any slide, which will be more fully described hereinafter.

Extending across and below the space between the magazine and the front wall of the casing is a chute 21 directed toward a delivery shelf 22 exposed exteriorly of the machine for the entire width of the magazine. Protecting the space above said shelf and certain mechanisms adjacent thereto, but co-operating with the chute 21, is a frame 23 which may either contain directions for the operation of the machine, or specimens of the merchandise contained in the various tiers of compartments 17. At the top of the machine is a frame 24 which may be used for the same purposes as the frame 23. The front of the casing 10 terminates well above the delivery end of the chute 21, as shown more particularly in Figs. 1 and 2, thus avoiding likelihood of the jambing of the outlet to the machine by the merchandise being delivered.

The chute 21 in addition to receiving and directing the merchandise to upon the delivery shelf 22, also, with this shelf, serves to close and protect those portions of the mechanisms the functioning of which is essential to the operation of the machine.

Mounted in each compartment 17 is a slide containing a magnetic substance toward the front thereof so as to permit this slide to be moved by an electro-magnetic plunger outwardly of the compartment toward the front of the machine for the purpose of causing the merchandise stored in the compartment in which it is slidably mounted to be delivered in relation to the chute 21. Each of these slides is identical in construction with every other, and a description of but one of

them will be entered into, reference being had more particularly to Fig. 3 of the drawings, although it is not desired to limit the invention to the detailed construction of the 5 slide shown, since this may be varied without in any wise modifying the operative effect of the machine.

The slide shown in the accompanying drawings, which is in the nature of a drawer 10 open at both the top and the bottom thereof, consists of a rear member and a forward member adapted to telescope in relation to each other, the forward member being capable of movement with, or movement independently of, the rear member according 15 to whether the actuation of the slide is by means of an electro-magnetic plunger or by purely mechanical means as when trying to defraud the machine. The rear member of 20 the slide consists of a looped portion 25 preferably of iron, steel, or other magnetic material, and having a capacity to receive the largest sized article with which the magazine is to be charged. Carried rearwardly of 25 this loop is an ejector block 26 which when the slide is drawn forwardly of the magazine will move the article to be delivered along the bottom of the compartment in which the slide is mounted, until it escapes 30 through the open bottom of the slide and falls upon the chute 21. The ejector block 26 is so positioned, as to its forward face with relation to the sides of the looped portion 25, as to prevent the escape of the slide 35 in its entirety from the compartment, permitting the article only to pass to the chute and leaving the slide in its outermost position as shown in Fig. 2. The forward member of the slide consists of a looped portion 40 27 open at the back so as to permit the sides thereof to have a free sliding movement between the sides of the looped portion 25 and the partitions 18 forming the vertical walls of the compartment. This portion 27 may be 45 made either of magnetic or non-magnetic material, although in the form of the invention shown it is made of non-magnetic material. The end of the looped portion 27 has an opening 28 therethrough closed by a 50 screen or fabric 29 which will permit the electro-magnetic plunger to be brought into close relation with the front of the looped portion 25.

The electro-magnetic plunger 30 has an 55 electro non-conductive handle 31 and an electro magnet 32 projecting therefrom. The core of this magnet is inclosed except as to the end thereof which is enlarged as shown at 33, by a jacket 34 of brass or other non-magnetic material which will admit of the 60 free movement of the plunger through the openings 13. Carried by the jacket 34 is a spring dog or dogs 35 which are within the magnetic field of the core 32 so that while 65 said dog or dogs are normally thrust out-

wardly to an extent to prevent their passing through an opening 13, when the magnet is energized they will be retracted within recesses in the jacket 34 to an extent to pass through the opening. The support for said 70 dogs is near the end 33 of the core of the magnet 32 and between same and the handle 31, said dog or dogs being so set as to have their normally projected ends towards the end 33. 75

The winding of the magnet 32 is arranged in a normally open circuit with a source of electrical supply, as the primary battery 36, means being provided in said circuit whereby it may be arbitrarily closed to energize 80 said magnet or the plunger. This means comprises two spaced contacts 37-38, one of which, as 37, is fixed and the other, 38, is movable but held at a set distance from the fixed contact by a stop pin 39 with which it is normally engaged by a spring 40. Flexible conductor wires 41 are connected with a lead 42 from the contact 37 and with one terminal of the battery 36 by a lead 43. The contacts 37-38 are spaced apart sufficiently 85 to receive and retain a coin or check delivered to the space between said contacts and in electrical contact with both. 90

Since when the plunger is once energized, it is operative to draw a slide from its compartment, and hence cause the delivery of an article by the machine, it is essential to provide automatically acting means for making the mechanism for energizing the plunger inoperative upon the delivery of the 95 article so as to restrict the operation of said plunger to the delivery of a single article each time it is energized. To prevent the de-energizing of the plunger until an article is actually delivered, we provide means operated by the article itself, so that if a compartment should be empty, the purchaser, after withdrawing the slide from that compartment, may withdraw the plunger through one opening 13, and insert it in another or other of such openings until a 100 charged compartment is found. 105

This automatically acting means, in the form of the invention shown, comprises two parallel bus bars 44-45, one of which, 44, 110 is connected by the conductor wire 46 with one terminal of the winding of an electro magnet 47 operative upon the movable contact 38 in opposition to the spring 40. The other bar 45 is connected by a wire 48 with 115 the lead 43 from the battery. 120

Said bars 44-45 are located above the delivery end of the chute 21 and one of them, as 44, has mounted thereon and electrically connected therewith, a sequence of highly 125 flexible, spring tentacles 49 of electro conductive material which depend therefrom across the other bar, but normally out of electrical engagement therewith, to a point closely adjacent the chute 21. Hence, irre- 130

spective of the compartment from which an article may be delivered, it must, in passing from the chute 21 to the shelf 22, engage some one or more of these tentacles and flex 5 the same sufficiently to engage it with the other bar 45 and close the circuit to the magnet 47, which when energized will separate the contacts 37-38 and permit the coin or check to drop therebetween, thus interrupt- 10 ing the circuit to the plunger 30. The circuit to the plunger 30 is completed through the wire 50 from the battery to the movable contact 38, and that to the magnet 47 through the wire 51 leading from the terminal of the 15 magnet winding to the battery.

The operation of the herein described vending machine is substantially as follows:—

Under normal conditions the circuit to the 20 electromagnetic plunger 30 is open so that this plunger is inoperative to impart movement to the slide in any compartment 17, the circuit to the magnet 47 also being normally open. This condition is to conserve battery 25 energy.

When a coin or check is inserted in the coin slot 20, it will descend until it engages, and spans the gap between, the contacts 37-38, and thus close the circuit to, and energize, the electro-magnetic plunger 30-33. While we prefer to close this circuit through the coin itself, it is apparent that a check or coin controlled mechanism may be used for completing this circuit in any desired manner so long as the circuit may be interrupted by movement of the contact 38.

The electro-magnetic plunger being thus energized, it may be passed through any opening 13 into engagement with the slide 40 in the compartment opposite said opening 13, there being insufficient play of said plunger in said opening to permit the plunger to operatively engage more than one slide. The magnetic traction of the plunger is suffi- 45 ciently great to cause it to draw the rear member of the slide from its compartment, as the plunger is withdrawn through the opening 13.

As the slide is thus drawn from its compartment it will bring with it the article stored in the compartment until the slide has had sufficient movement to permit the article to fall through the open bottom of the slide and the space between the magazine and the front of the casing 10 upon the chute 21 along which it will pass to the delivery shelf 22 where it is accessible to the purchaser. If lower slides had, prior to the actuation of an upper slide, been withdrawn 55 from their compartments, the article may pass through such slides, since each slide is open at the top as well as at the bottom.

If dogs 35 be used, they will be drawn within the recesses of the jacket 34 when the 60 plunger is energized, but will be projected

beyond the outer face of said jacket at all other times, thus preventing the plunger being used to return slides which have once been withdrawn, to their compartments. The use of such dogs, while desirable, is not 70 essential, and they are employed merely to discourage tampering with the machine.

An article in passing from the chute 21 upon the shelf 22 must engage one or more of the spring tentacles 49 and close the circuit across the bus bars 44-45 to the magnet 47 which being thus energized will attract the movable contact 38 and open the circuit to the plunger 30, or make the means closing this circuit inoperative to energize said 80 plunger, upon the delivery of the article. It is to be noted that the deenergizing of the plunger 30 is dependent upon the actual delivery of an article, so that in the event of a compartment being empty, the operator may 85 freely withdraw the plunger through one opening 13, and by passing it through another or other of such openings withdraw a slide from another or other compartments until an article is delivered.

Immediately that an article passes the line or sequence of tentacles 49, the displaced tentacles will spring away from the bus bar 45, thus instantly reopening the circuit to the magnet 47 preparatory to the next actuation of the machine.

If the magnetic plunger 30 be energized, when the end 33 is brought into the operative relation to a slide, both members of the slide will move in unison to accomplish the 100 delivery of an article. If, however, said plunger is not energized, no movement can be imparted to either member of the slide unless some adhesive substance be applied to the plunger, or a stick used in lieu thereof, 105 so as to mechanically connect it to the looped portion 27 of the forward member of the slide, whereupon this forward member alone will be drawn from the compartment leaving the rear member and the article within 110 the compartment. If the forward member be thus withdrawn, it will not interfere with an article falling from an upper compartment, since such an article may fall through the loop to upon the chute 21.

It will be observed that in a machine embodying the invention, the plunger 30 is normally inoperative to effect the delivery of an article from any compartment in the machine, and that when said plunger is energized so that it may impart movement to any slide which may be selected by the operator, it will remain operative only until an article has been delivered, the delivery of the article immediately restoring the plunger to its inoperative condition. The length of the flexible wire 41 is such as to permit the plunger to be used with any opening 13 in the unit operated by means of this plunger, so that if different units are closely associated for 115 120 125 130 135

the purpose of delivering articles having different values it is necessary to have a separate plunger for each unit.

The forward member of the slide including a loop 27 may be of magnetic material if desired, in which case the screen 29 need not be used.

It will be observed that in a machine embodying the invention, the construction and mechanisms employed are of the simplest form, and yet present in the machine adequate safeguards to ensure a purchaser receiving merchandise while preventing the fraudulent actuation of the machine.

15 While various structural variations may be made as to the details of the various slides and of the magnetic plunger, it is apparent that such changes would not modify the mode of operation of the machine which requires a mechanism by which the circuit to the plunger may be arbitrarily closed to permit the selective withdrawal of a slide from some compartment of the machine in the manner above described, and the automatic 25 opening of the circuit to this plunger resulting from the delivery of the article so as to prevent the withdrawal of more than a single slide with one actuation of the means causing the plunger to be energized, 30 unless this operation is not accompanied by the delivery of an article.

It is not our intention to limit the invention to the precise details of construction shown in the drawings, it being apparent 25 that such may be varied without departing from the spirit and scope of the invention.

Having described the invention, what we claim as new and desire to have protected by Letters Patent, is:—

40 1. A vending machine embodying therein a casing, a plurality of merchandise receiving compartments, a slide containing electro-magnetic material in each compartment and engaging the merchandise therein, whereby movement of said slide outwardly of the compartment will eject the merchandise from the compartment, said casing having openings therethrough, an electro-magnetic plunger adapted to be passed through 45 any of said openings into operative relation to a slide, a source of electrical supply, means arranged in circuit with said plunger and said source of supply whereby said plunger may be energized upon the insertion 50 of a check, a delivery shelf adapted to receive articles, and means operable as a result of the delivery of an article by the machine for making said last named means inoperative.

55 2. A vending machine embodying therein a casing, a plurality of merchandise receiving compartments, a slide containing electro-magnetic material in each compartment and engaging the merchandise therein, 60 whereby movement of said slide outwardly

of the compartment will eject the merchandise from the compartment, said casing having openings therethrough, an electro-magnetic plunger adapted to be passed through any of said openings into operative relation 70 to a slide, a source of electrical supply, normally open electrical contacts, one of which is movable in relation to the other, arranged in circuit with the plunger and said source of supply, said contacts being spaced apart 75 so as to require the insertion of an electro-conductive article in electrical contact with both said contacts to close the circuit to energize said plunger, a delivery shelf adapted 80 to receive articles, means whereby said movable contact may have movement imparted thereto to cause the interruption of the circuit to said contact, and means arranged in the path of movement of an article to said shelf, whereby said last named means will be 85 actuated as a result of the delivery of an article to cause said plunger to be de-energized.

3. A vending machine embodying therein a casing, a plurality of merchandise receiving compartments, a slide containing electro-magnetic material in each compartment and engaging the merchandise therein, whereby movement of said slide outwardly of the compartment will eject the merchandise from 95 the compartment, said casing having openings therethrough, an electro-magnetic plunger adapted to be passed through any of said openings into operative relation to a slide, a source of electrical supply, normally 100 open electrical contacts, one of which is movable in relation to the other, arranged in circuit with the plunger and said source of supply, said contacts being spaced apart so as to require the insertion of an electro-conductive article in electrical contact with both said contacts to close the circuit to energize said plunger, a stop positioning said 105 movable contact in relation to said fixed contact, a spring tending to normally engage 110 said movable contact with said stop, a delivery shelf adapted to receive articles, means acting in opposition to said spring whereby said movable contact may have movement imparted thereto to cause the interruption of the circuit to said contact, and means arranged in the path of movement of an article to said shelf, whereby said last 115 named means will be actuated as a result of the delivery of an article to cause said 120 plunger to be de-energized.

4. A vending machine embodying therein a casing, a plurality of merchandise receiving compartments, a slide containing electro-magnetic material in each compartment 125 and engaging the merchandise therein, whereby movement of said slide outwardly of the compartment will eject the merchandise from the compartment, said casing having openings therethrough, an electro-mag- 130

netic plunger adapted to be passed through any of said openings into operative relation to a slide, a source of electrical supply, means arranged in circuit with said plunger and said source of supply whereby said plunger may be energized upon the insertion of a check, a delivery shelf adapted to receive articles, bus bars, an electro-magnet operative upon the means for energizing said plunger, and arranged in circuit with said source of supply and said bus bars, and a sequence of spring tentacles of electro-conductive material, mechanically and electrically connected with one of said bus bars and adapted to be engaged with the other bus bar, said tentacles projecting in the path of movement of an article to said delivery shelf, whereby the movement of any of said tentacles by an article passing to said shelf will energize said magnet and cause said plunger to be de-energized.

5. A vending machine embodying therein a casing, a plurality of merchandise receiving compartments, a slide containing electro-magnetic material in each compartment and engaging the merchandise therein, whereby movement of said slide outwardly of the compartment will eject the merchandise from the compartment, said casing having openings therethrough, an electro-magnetic plunger adapted to be passed through any of said openings into operative relation to a slide, a source of electrical supply, normally open electrical contacts, one of which is movable in relation to the other, arranged in circuit with the plunger and said source of supply, said contacts being spaced apart so as to require the insertion of an electro-conductive article in electrical contact with both said contacts to close the circuit to energize said plunger, a stop positioning said movable contact in relation to said fixed contact, a spring tending to normally engage said movable contact with said stop, a delivery shelf adapted to receive articles, bus bars, an electromagnet operative upon said movable contact, and arranged in circuit with said source of supply and said bus bars, and a sequence of spring tentacles of electro-conductive material, mechanically and electrically connected with one of said bus bars and adapted to be engaged with the other bus bar, said tentacles projecting in the path of movement of an article to said delivery shelf, whereby the movement of any of said tentacles by an article passing to said shelf will energize said magnet and cause said plunger to be de-energized.

6. A vending machine embodying therein a casing, a plurality of merchandise receiving compartments, each compartment having therein a slide comprising telescopic forward and rear members, each open at the top and at the bottom thereof, said rear member containing at the forward edge thereof electro-magnetic material, and toward the rear thereof a block for engagement with an article in the compartment, and said forward member being movable independently of, or by, the rear member, whereby mechanical actuation of the slide to cause the delivery of an article is prevented, said casing having openings therethrough, an electro-magnetic plunger adapted to be passed through any of said openings into operative relation to a slide, a source of electrical supply, means arranged in circuit with said plunger and said source of supply whereby said plunger may be energized upon the insertion of a check, a delivery shelf adapted to receive articles, and means operable as a result of the delivery of an article by the machine for making said last named means inoperative.

7. A vending machine embodying therein a casing, a plurality of merchandise receiving compartments, each compartment having therein a slide comprising telescopic forward and rear members, each open at the top and at the bottom thereof, said rear member containing at the forward edge thereof electro-magnetic material, and toward the rear thereof a block for engagement with an article in the compartment, and said forward member being movable independently of, or by, the rear member, whereby mechanical

any of said openings into operative relation to a slide, a source of electrical supply, normally open electrical contacts, one of which is movable in relation to the other, arranged in circuit with the plunger and said source of supply, said contacts being spaced apart so as to require the insertion of an electro-conductive article in electrical contact with both said contacts to close the circuit to energize said plunger, a stop positioning said movable contact in relation to said fixed contact, a spring tending to normally engage said movable contact with said stop, a delivery shelf adapted to receive articles, bus bars, an electromagnet operative upon said movable contact, and arranged in circuit with said source of supply and said bus bars, and a sequence of spring tentacles of electro-conductive material, mechanically and electrically connected with one of said bus bars and adapted to be engaged with the other bus bar, said tentacles projecting in the path of movement of an article to said delivery shelf, whereby the movement of any of said tentacles by an article passing to said shelf will energize said magnet and cause said plunger to be de-energized.

7. A vending machine embodying therein a casing, a plurality of merchandise receiving compartments, each compartment having therein a slide comprising telescopic forward and rear members, each open at the top and at the bottom thereof, said rear member containing at the forward edge thereof electro-magnetic material, and toward the rear thereof a block for engagement with an article in the compartment, and said forward member being movable independently of, or by, the rear member, whereby mechanical actuation of the slide to cause the delivery of an article is prevented, said casing having openings therethrough, an electro-magnetic plunger adapted to be passed through any of said openings into operative relation to a slide, a source of electrical supply, means arranged in circuit with said plunger and said source of supply whereby said plunger may be energized upon the insertion of a check, a delivery shelf adapted to receive articles, and means operable as a result of the delivery of an article by the machine for making said last named means inoperative.

8. A vending machine embodying therein a casing, a plurality of merchandise receiving compartments, each compartment having therein a slide comprising telescopic forward and rear members, each open at the top and at the bottom thereof, said rear member containing at the forward edge thereof electro-magnetic material, and toward the rear thereof a block for engagement with an article in the compartment, and said forward member being movable independently of, or by, the rear member, whereby mechanical

- actuation of the slide to cause the delivery of an article is prevented, both members of said slide being of a length to prevent their complete withdrawal from a compartment, 5 said casing having openings therethrough, an electro-magnetic plunger adapted to be passed through any of said openings into operative relation to a slide, a source of electrical supply, means arranged in circuit with 10 said plunger and said source of supply whereby said plunger may be energized upon the insertion of a check, a delivery shelf adapted to receive articles, and means operable as a result of the delivery of an article by the machine for making said last named means inoperative.
9. A vending machine embodying therein a casing, a magazine containing a plurality of merchandise receiving compartments 20 spaced rearwardly from the front of said casing, each compartment having therein a slide comprising telescopic forward and rear members, each open at the top and at the bottom thereof, said rear member containing 25 at the forward edge thereof electro-magnetic material, and toward the rear thereof a block for engagement with an article in the compartment, and said forward member being movable independently of, or by, the 30 rear member, whereby mechanical actuation of the slide to cause the delivery of an article is prevented, both members of said slide being of a length to prevent their complete withdrawal from a compartment, said 35 casing having openings therethrough, an electro-magnetic plunger adapted to be passed through any of said openings into operative relation to a slide, a source of electrical supply, means arranged in circuit 40 with said plunger and said source of supply whereby said plunger may be energized upon the insertion of a check, a delivery shelf adapted to receive articles, a chute extending at an incline from adjacent the bottom of said magazine across the space between said magazine and the front of the machine and toward said delivery shelf, bus bars, an electromagnet operative upon said movable contact and arranged in circuit with said source of supply and said bus bars, and a sequence 45 of spring tentacles of electro-conductive material, mechanically and electrically connected with one of said bus bars and adapted to be engaged with the other bus bar, said tentacles projecting in the path of movement of an article to said delivery shelf, whereby the movement of any of said tentacles by an article passing to said shelf will energize said magnet and cause said plunger to be de- 50 energized.
11. A vending machine embodying therein a casing, a plurality of merchandise receiving compartments, a slide containing electro-magnetic material in each compartment and engaging the merchandise therein, whereby movement of said slide outwardly of the compartment will eject the merchandise from the compartment, said casing having openings therethrough, an electro-magnetic plunger adapted to be passed through any of said openings into operative relation to a slide, electro-magnetically operated means carried by said plunger, whereby its passage through an opening is 55 prevented except when the plunger is energized, a source of electrical supply, means arranged in circuit with said plunger and said source of supply whereby said plunger may be energized upon the insertion of a check, a delivery shelf adapted to receive 60 articles, and means operable as a result of the delivery of an article by the machine for making said last named means inoperative.
12. A vending machine embodying therein a casing, a plurality of merchandise receiving compartments, a slide containing electro-magnetic material in each compartment and engaging the merchandise therein, whereby movement of said slide outwardly of the compartment will eject the merchandise 65 from the compartment, said casing having openings therethrough, an electro-magnetic plunger adapted to be passed through any of said openings into operative relation to a slide, said plunger comprising an electro- 70 non-conductive handle, an electro-magnet projecting therefrom, a non-magnetic metallic jacket inclosing said magnet, the core of said magnet projecting beyond said jacket, and spring contacts carried in re- 75

cesses in said jacket and within the magnetic field of said core, whereby insertion of said plunger in an opening is prevented except when it is energized, a source of electrical supply, means arranged in circuit with said plunger and said source of supply whereby said plunger may be energized upon the insertion of a check, a delivery shelf adapted to receive articles, and means operable as a

result of the delivery of an article by the machine for making said last named means inoperative.

In witness whereof we have hereunto affixed our signatures, this 31st day of December, 1924.

WALTER GOODCHILD.
NATHAN SCLAR.
